REGULATING VALVE FOR CARBURETORS

Edward T. Condon, New York, N. Y.

Application November 14, 1933, Serial No. 697,899

5 Claims. (Cl. 123—119)

The invention relates to an air regulating device for use with the carburetors of internal combustion engines, and more especially to an automatic air controlling device for regulating the supply of air to the carburetor in accordance with the variations of load placed upon the internal combustion engine which may be of the conventional type and with which the carburetor is associated in the usual manner in supplying fuel thereto for its operation.

I am aware that it has been proposed to associate with the carburetor of an internal combustion engine means located within the air intake passage of the carburetor in the nature of a swinging disk or butterfly valve, said means being actuated by a pneumatic device controlled in accordance with the fluctuations of the pressure prevailing in a connection, or the engine manifold, between the throttle valve of the carburetor and the said engine. In the use of these means, however, it has been the practice to install a blocking butterfly valve which is of substantially the same diameter as the internal diameter of the air intake passage and within which said valve is mounted to swing. In other words, it constituted an auxiliary choke serving under certain conditions to cut off fully the introduction of air to the carburetor. This, I have found, will render the carburetor ineffective for maintaining operation of the engine under all conditions, particularly at the higher speeds and under which conditions the pressure in the controlling space, and as a result of which the valve is actuated, rises substantially to atmospheric pressure so that practical closing-off of the air supply to the carburetor results from the positioning of the regulating valve. The exceedingly rich mixture then supplied to the engine thus not only causes it to stall but will so flood the carburetor that restarting of the hot engine will be difficult, if not impossible, until it has again cooled.

The present invention has for an object the provision of a regulating valve device for use with carburetors and whereby, while the air supply through the valve is variable in accordance with the demands of the engine, the device will nevertheless provide for a predetermined and ample supply of air to obviate under all operating conditions any stalling of the engine as well as affording instantaneous starting when the engine is hot, and to afford at the same time a means for cutting off substantially all of the air as for starting the engine when it is cold.

55 In the accompanying drawing, which illus-

trates a practical embodiment of my invention, Fig. 1 is a fragmentary view of an engine head, including the carburetor, (both shown in phantom lines) with the novel regulating device associated with the carburetor and engine and indicated in full lines.

Fig. 2 is a vertical section of the novel regulating device.

Fig. 3 is a plan thereof, but with the regulating members shown in cooperating position to close off the air supply.

Fig. 4 is a fragmentary vertical section illustrating the relative positions of the valve member and choke ring during operation of the engine.

Referring to Fig. 1 of the drawing, the internal combustion engine is indicated at 10, the same being provided with the usual manifold 11 for receiving properly atomized liquid fuel derived from the carburetor 12 which is equipped with the usual throttle valve 13 for supplying the engine with the required quantity of fuel. The novel regulating valve, indicated by the full lines, is shown installed at the outer end of the air intake passageway 14 of the carburetor.

This is conveniently effected by means of a sleeve or adapter member 15 of the regulating device being fitted within the said outer end of said air intake passageway 14. The adapter member is preferably made as a unit, separable from the casing 16 of the regulator valve device, having a close fit within the interior of the passageway 14; and is secured in position by set screws 17 passing through the wall of the said adapter.

The casing 16 is tubular in form, having the through passageway 18; and there is mounted between the ends of the same a circular disk or regulator member 19 which is designed to be angularly movable or variously locatable therein with reference to the air flow, as through trunnions carried in the bearings 20 and 21 rotatably mounted in the casing.

Movement for displacing this disk angularly is obtained from a piston 25 reciprocable within a cylinder 26 in accordance with the pressure prevailing in the connection between the throttle valve 13 and the engine, for example in the manifold 11. To this end, a connection 27 is taken from the one end 28 of the cylinder 26 to the said manifold 11, the said cylinder being preferably formed as a unit with the said casing 16.

The piston rod 29 connected to piston 25 extends beyond the opposite end of cylinder 26 and a spring 30 coiled about the outer end tends

to bias the piston in a direction to maintain the disk or butterfly valve 19 in a position transverse to the passageway 18 through cylindrical casing 16, as indicated in Figs. 2 and 3.

5 However, when the pressure within cylinder 26 falls below atmospheric pressure due to the production of more or less of a vacuum in the manifold space, piston 25 is advanced in its cylinder 26 carrying the rod 23 with it, and the motion of the 10 latter is communicated to the butterfly valve 19 through intermediate connecting means including the crank-arm 31 forming an extension of the trunnion of the butterfly valve, and an arm 32 pivoted to said crank-arm. By this expedient, 15 the reciprocations of the piston 25 will be communicated to the butterfly valve 19 to swing the same through an angle of 90 degrees or from a position transverse to the passageway 18 to a position (shown in Fig. 4) parallel to the axis 20 of said passageway, the said valve assuming various intermediate positions and thus controlling the admission of air through the said passageway and to the carburetor.

However, in accordance with the invention, the 25 butterfly valve 19 is so constructed that it will not completely shut off the supply of air through the said passageway but provides for a predetermined leakage past or through the said valve. To this end, its diameter may be made substantially less 30 than the cross-sectional area of the said passageway so as to accord a permanently open area or annulus 33, as between the circumference of said disk and the inner casing wall. This will admit of the introduction of air to the carburetor irrespective of the position of said disk, while its particular angular position will determine the introduction of additional air to the carburetor in accordance with the demands of the engine.

In addition, provision is made for temporarily 40 closing off the annular space 33 about the disk or butterfly valve 19 so that, for example, in starting the engine cold the benefit of a substantially full choke may be had. To this end, the rotatable bearings 20, 21, carry an annular member 45 or choke ring 34, concentric with the butterfly valve 19 and circumscribing the same, said ring being of a width substantially equal to the width of the annulus 33. During operation of the engine this choke ring will be positioned under the 50 action of a biasing spring 35 to a location, Figs. 2 and 4, parallel to the flow direction through the casing, and it will thus be substantially without effect upon the flow. The position of the choke ring may also be altered, for the purpose herein- 55 after set forth, by acting on the arm 36, connected to bearing 20, either manually or thermos- 60 statically, as is well understood in the art. No claim, however, is made herein to the particular manner of controlling the position of ring 34, the 65 invention contemplating solely the provision of the said choke ring and its cooperation with the disk to effect a substantial closure, Fig. 2, of the passageway 18 when, for example, it is desired to start a cold engine.

In initially adjusting the valve position, the 70 disk 19 is set substantially vertical or parallel to the air flow so as to afford the correct and leanest possible proportions of air and atomized fuel for idling operation of the engine; and the minimum area of opening represented by annulus 33 is so selected that proper combinations of fuel 75 and air will be maintained at high speeds of the engine. This minimum area will be approximately from 35% to 40% of the cross-sectional area of the casing.

Thus, by running the engine at idling speed with full opening of the valve member in accordance with the pressure prevailing in the engine manifold, the proportionate area or areas of the fuel jet or jets of the carburetor may be adjusted to 5 suit. This will determine the correct proportions at the various engine speeds and will secure correct and complete carburetion throughout so as to eliminate production of carbon monoxide in the engine exhaust. It is to be noted, also, that 10 with the novel device installed the response to any change in fuel demand will be rapid and without substantial lag.

When a particularly rich mixture is required as in starting the engine cold, the choke ring 34 15 will be manually positioned transversely to the passageway 18, as indicated in Fig. 3; and the disk 19 (initially horizontal) will with ring 34 temporarily cut off the inflow of air through the air intake passage of the carburetor until sufficient vacuum is set up in the cylinder 26 to overcome the spring pressure exerted by spring 30. It will be appreciated, therefore, that the usual choke valve of a carburetor may be dispensed with, as the ring 34 in cooperation with the disk 25 19 may serve to effectively block temporarily all admission of air to said carburetor.

I claim:

1. The combination with a carburetor having an air intake passage and a throttle valve and adapted for use with an internal combustion engine provided with an intake pipe, of a regulating valve for the air supplied to the carburetor, said valve comprising a casing having a through passageway and adapted to be fitted to the carburetor air intake passage, pneumatically operating means associated with the casing adapted for communication with the engine intake pipe beyond the throttle valve of the carburetor, a valve member movably mounted within the casing to swing about an axis perpendicular to the longitudinal axis of said casing and of an effective area substantially less than the cross-sectional area of the casing passageway to afford a predetermined circular opening for the introduction of air to the carburetor irrespective of the position of said valve member, means connecting the latter with the pneumatically operating means, and a member movably mounted within the casing adapted to fit within the predetermined opening provided by the said valve member to cut off substantially the flow of air through the said casing, and means to bias said movably mounted member to normally position the same parallel to the flow through the casing.

2. The combination with a carburetor having an air intake passage and a throttle valve and adapted for use with an internal combustion engine provided with an intake pipe, of a regulating valve for the air supplied to the carburetor, 60 said valve comprising a casing having a through passageway and adapted to be fitted to the carburetor air intake passage, pneumatically operating means associated with the casing adapted for communication with the engine intake pipe 65 beyond the throttle valve of the carburetor, a circular valve member rotatably mounted within the casing and of a diameter substantially less than the cross-sectional area of the casing passageway to afford a predetermined annular opening for the introduction of air to the carburetor irrespective of the position of said valve member, means connecting the latter with the pneumatically operating means, and a choke ring, rotatably mounted within the casing about the said 70 75

valve member and adapted to fit within the annular opening provided thereby to cut off with the valve member flow of air through the said casing, and means to bias said choke ring to normally 5 position the same parallel to the flow through the casing.

3. The combination with a carburetor having an air intake passage and a throttle valve and adapted for use with an internal combustion engine 10 provided with an intake pipe, of a regulating valve for the air supplied to the carburetor, said valve comprising a casing having a through passageway and adapted to be fitted to the carburetor air intake passage, pneumatically operating 15 means associated with the casing adapted for communication with the engine intake pipe beyond the throttle valve of the carburetor, a circular valve member rotatably mounted within the casing and of a diameter substantially less than 20 the cross-sectional area of the casing passageway to afford a predetermined annular opening for the introduction of air to the carburetor irrespective of the position of said valve member, means connecting the latter with the pneumatically 25 operating means, and a choke ring rotatably mounted within the casing and concentric with the said valve member to circumscribe the latter and cooperate therewith for closing the annular opening provided thereby and cut off flow of air 30 through the casing, and means to bias said choke ring to normally position the same parallel to the flow through the casing.

4. The combination with a carburetor having an air intake passage and a throttle valve and 35 adapted for use with an internal combustion engine provided with an intake pipe, of a regulating valve for the air supplied to the carburetor, said valve comprising a casing having a through passageway and adapted to be fitted to the carburetor air intake passage, pneumatically operating 40 means associated with the casing adapted for communication with the engine intake pipe beyond the throttle valve of the carburetor, a circular valve member, trunnions extending radially 45 of the valve member to support the same within

the casing, said valve member being of a diameter substantially less than the cross-sectional area of the casing passageway to afford a predetermined annular opening for the introduction of air to the carburetor irrespective of the position of said valve member, means connecting the latter with the pneumatically operating means, rotatable bearings for the trunnions of said valve member, and a choke ring carried by the said trunnions, concentric with the said valve member 10 to circumscribe the latter and cooperate therewith for closing the annular opening provided thereby and cut off flow of air through the casing, and means to bias said choke ring to normally 15 position the same parallel to the flow through the casing.

5. The combination with a carburetor having an air intake passage and a throttle valve and adapted for use with an internal combustion engine 20 provided with an intake pipe, of a regulating valve for the air supplied to the carburetor, said valve comprising a casing having a through passageway and adapted to be fitted to the carburetor air intake passage, pneumatically operating 25 means associated with the casing adapted for communication with the engine intake pipe beyond the throttle valve of the carburetor, a circular valve member rotatably mounted within the casing and of a diameter substantially less than 30 the cross-sectional area of the casing passageway to afford a predetermined annular opening for the introduction of air to the carburetor irrespective of the position of said valve member, means connecting the latter with the pneumatically 35 operating means, a choke ring rotatably mounted within the casing and concentric with the said valve member to circumscribe the latter and cooperate therewith for closing the annular opening provided thereby and cut off flow of air 40 through the casing, said ring in its normal position being biased to a position parallel to the longitudinal axis of the casing and substantially at right angles to the valve member when the engine is inoperative.
